John B. Goodwin

Inventor:

UNITED STATES PATENT OFFICE.

JOHN B. GOODWIN, OF BALTIMORE, MARYLAND.

DESIGN FOR A BADGE OR SIMILAR ARTICLE.

No. 37,888.

Specification for Design.

Patented March 13, 1906.

Application filed February 7, 1906. Serial No. 299,372. Term of patent 14 years.

To all whom it may concern.

Be it known that I, JOHN B. GOODWIN, a citizen of the United States, residing in the city of Baltimore, State of Maryland, have invented and produced a new and original Design for Badges or Similar Articles, of which the following is a specification, reference being had to the accompanying drawing, forming part thereof.

The figure is a front view of a badge, showing my new design.

I claim—

The ornamental design for a badge or similar article, as shown.

JOHN B. GOODWIN.
